DISPLAY CASE

Robert E. Pellow, Waco, Tex.

Application July 12, 1932. Serial No. 622,142

2 Claims. (Cl. 312—114)

The invention relates to merchandise cases and more especially to display cases for merchandise.

The primary object of the invention is the provision of a case of this character, wherein the body thereof is of a particular construction so that it may be swingingly supported whereby on the raising of the body access may be had to articles for display thereby, the case being readily portable and adapted to be positioned upon a suitable support for the display of merchandise, particularly small articles.

Another object of the invention is the provision of a case of this character, wherein the same when upon a support will be prevented from slipping or becoming disarranged and will display articles of merchandise, the latter being protected and the said case thoroughly sanitary.

A further object of the invention is the provision of a case of this character which is simple in construction, thoroughly reliable and efficient in its purpose, neat and attractive in appearance, assuring full display of articles of merchandise when held therein, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claims hereunto appended.

In the accompanying drawing:

Figure 1 is a top plan view of a display case constructed in accordance with the invention and the same being partly broken away.

Figure 2 is an end elevation thereof.

Figure 3 is a view similar to Figure 2 showing the body of the case in raised position.

Figure 4 is an enlarged sectional view on the line 4—4 of Figure 1.

Figure 5 is a fragmentary detail perspective view of the pivot for the body of the case.

Figure 6 is a fragmentary perspective view of one corner portion of the body showing a slight modification.

Similar reference characters indicate corresponding parts throughout the several views in the drawing.

Referring to the drawing in detail, the display case comprises a base 10 which is preferably elongated or of rectangular form and is provided at its front edge with a downturned flange 11 coextensive with the length of the base to con-

stitute an abutment when the base 10 is superimposed upon a support such as a counter, stand or the like to prevent rearward displacement of the case or disarrangement thereof in the use of the same.

Mounted upon the base near opposite rear corners of the same are brackets 12, these having upstanding pivot ears 13 for swingingly supporting the body of the case as will be herein-after fully described.

The body of the case comprises end pieces 14, these being made preferably from wood although the same may be made from any other material, the pieces at their upper portions being rounded and fitted about the sides and upper rounded portions of said pieces is a transparent covering 15 made from any suitable material, the end edges of the latter being made secure through the medium of bands 16, preferably metal strips which are secured by fasteners 17 passed therethrough and engaged in the pieces 14. These bands 16 are disposed transversely of the body while at the bottom edges of said body and coextensive with the longitudinal sides thereof are channeled bands or strips 18, these being made secure through the medium of fasteners 19 with the covering and are preferably made from metal.

The channeled strip at the bottom rear longitudinal edge has joined therewith pintles 20, these being engaged in the ears 13 so that the body will be swingingly connected with the base 10.

The base 10 has countersunk therein a contact plate 21, while the covering 15 medially of its length has fitted thereto transversely of the same inside and outside bands 22 and 23 respectively, the outside band being carried beneath the channeled strip at the rear bottom edge of the body and upwardly to overlie the inside band 22 and this portion 24 of said outside band 23 is made with a rounded bend 25 to coact with the contact plate 21 so as to assure a fulcrum intermediate of the body of the case and for free swinging movement of said body on the raising and lowering thereof onto and from the base 10.

Each end piece 14 has fixed thereto a brace or bracket 26, the same being made fast to an intermediate longitudinally disposed inner band or strip 27 upon the body and against the covering 15 so as to assure strength to the body.

The body at its front has thereon a hand knob 28, the latter being preferably fixed to the front channeled strip at the point of the cross-

ing thereof with the inner and outer intermediate transverse strips 22 and 23 and this knob permits the convenient raising and lowering of the body onto and from the base 10.

5 It will be apparent that articles of merchandise can be placed upon the base 10 and confined within the body of the case when lowered upon this base and display thereof had through the covering 15 of the body.

10 In Figure 6 of the drawing there is shown a slight modification wherein in lieu of the channeled strips 18 flat strips 29 are substituted, these being suitably secured in overlapping relation to each transverse band 30 and arranged 15 at the end pieces 31 of the body to overlap a short distance the bottom edge of each end piece 31 and also the end of the strip 29 is a felt pad 32, this functioning to prevent slipping of the body which is independent and 20 separate from a base as in this modified form the base hereinbefore described is dispensed with, the body constituting the show case in the modified form being superimposed upon a counter or other like stand.

25 In the use of the display case without the base as is illustrated in Figure 6 of the drawing it is preferable to have the opening side of the body or the front thereof bearing the handle rail with the latter of a width to extend below 30 the plane of the bottom edge of the body so that this rail will lock against the edge of the counter or other table-like support to hold the body in place and against movement in a rearward direction on the support. In other words this 35 rail will be in lieu of the flange 11 and will be

directly carried by and a part of the body of the case.

What is claimed is:

1. A display case comprising spaced end pieces having upper rounded portions and straight bottom edges, substantially U-shaped strips secured to the end pieces next to the bottom straight edges thereof, a transparent covering about the end pieces at the upper rounded portions and having its longer edges received in said U-shaped strip, a band located between the end pieces and secured medially of and to the inner face of said covering, brackets carried by the end pieces and secured to said band at opposite ends thereof, and bands transversely disposed relative to the covering at the outer side thereof and joined with the U-shaped strips. 80 85 90 95

2. A display case comprising spaced end pieces having upper rounded portions and straight bottom edges, substantially U-shaped strips secured to the end pieces next to the bottom straight edges thereof, a transparent covering about the end pieces at the upper rounded portions and having its longer edges received in said U-shaped strips, a band located between the end pieces and secured medially of and to the inner face of said covering, brackets carried by the end pieces and secured to said band at opposite ends thereof, bands transversely disposed relative to the covering at the outer side thereof and joined with the U-shaped strips, a support, and means hingedly securing the case to the support. 100 105 110
